LIQUID DISPENSER

Albert T. Braga, West St. Paul, Minn., assignor to Whirlpool Corporation, a corporation of Delaware
Filed June 22, 1966, Ser. No. 559,557
2 Claims. (Cl. 222—76)

ABSTRACT OF THE DISCLOSURE

An electromagnetically operated dispenser for dispensing a preselected small quantity of water conditioning agent in a dishwasher or clothes washer.

The dispenser is a pump with a spring actuated, magnetically released plunger having a hammer action.

This invention relates to liquid dispensers and in particular to liquid dispensers providing a predetermined quantity of liquid at a predetermined time in the cycle of operation of apparatus with which the dispenser is associated.

In apparatus such as dishwashing, or clothes washing, apparatus, it is desirable at times to provide a small quantity of liquid such as a wetting agent as during the last rinse cycle. In a dishwashing cycle, such wetting agents have the desirable effect of reducing the surface tension of the rinse water, thereby effectively reducing spotting of the dishes and effectively decreasing the drying time. Where such wetting agents are used in clothes washing apparatus, the removal of the rinse water is facilitated as during the spin or centrifuging drying operation.

The present invention is concerned with an improved means for dispensing such a preselected small quantity of a liquid such as a wetting agent. Thus, a principal feature of the present invention is the provision of a new and improved liquid dispenser.

Another feature of the invention is the provision of such a liquid dispenser having new and improved means for effecting the discharge of a preselected quantity of liquid from a pump chamber as desired by the user.

A further feature of the invention is the provision of such a liquid dispenser arranged to utilize an automatic signal from the associated apparatus, but requiring a manual potentiation of the discharging means to permit the signal to effect a dispensing operation.

Still another feature of the invention is the provision of such a liquid dispenser having means defining a storage chamber and passage means for conducting the liquid to be dispensed from the storage chamber to the pumping chamber, the apparatus being arranged to provide a self-cleaning of the passage as a concomitant of a dispensing of the liquid.

A further feature of the invention is the provision of such a liquid dispenser having new and improved means for effecting the pumping of the liquid from a pumping chamber.

Still another feature of the invention is the provision of such a liquid dispenser having means defining a pumping chamber provided with an outlet, means for discharging a preselected quantity of liquid from the pumping chamber through the outlet comprising pumping means disposable in a potentiated arrangement and movable from the potentiated arrangement to provide a pumping stroke forcing a preselected quantity of liquid from the pumping chamber through the outlet, manually operable means for disposing the pumping means in the potentiated arrangement, means for releasably holding the pumping means in the potentiated arrangement, means providing a signal at preselected times, and means responsive to the signal for operating the holding means

2

to release the potentiated pumping means whereby the signal means effects a pumping stroke only when the pumping means has been manually potentiated prior to the provision of a signal by the signal means.

5 Other features and advantages of the invention will be apparent from the following description taken in connection with the accompanying drawing wherein:

FIGURE 1 is a side elevation of a dishwashing apparatus having a portion thereof broken away to illustrate the arrangement of a liquid dispenser embodying the invention therein;

FIGURE 2 is a front elevation of the liquid dispenser; FIGURE 3 is a side elevation thereof;

10 FIGURE 4 is a fragmentary front elevation illustrating the arrangement of the dispenser as upon completion of a dispensing operation; and

15 FIGURE 5 is a fragmentary enlarged vertical section taken substantially along the line 5—5 of FIGURE 4.

In the exemplary embodiment of the invention as dis-

20 closed in the drawing, a washing apparatus generally designated 10, here comprising a dishwashing apparatus, is shown to include a cabinet 11 having a rear wall 12 carrying a liquid dispenser, generally designated 13, embodying the invention. The dispenser 13 may include a

25 storage tank 14 for storing a quantity of the liquid L to be dispensed. Liquid is directed from the storage tank 14 into a pumping chamber 15 through a small orifice 16. In the illustrated embodiment, the pumping chamber 15 is disposed within the tank 14. As best seen in FIG-

30 URES 2 and 3, access to the interior of tank 14 is pro- 20 vided through an inlet opening 17 in cabinet wall 12, the tank 14 being provided with a tubular fitting 18 extending through opening 17 into the dishwashing chamber 19 forwardly of the wall 12. A conduit 20

35 extends upwardly from the pumping chamber 15 to have an outlet end 21 thereof disposed in the opening 17 within fitting 18 to discharge liquid from the pumping chamber 15 into the dishwashing chamber 19 at selected times.

40 Discharge of the liquid L from the outlet 21 is effected herein by means of a hammer 22 arranged to strike a flexible diaphragm 23 defining one wall of the chamber 15 at the bottom of tank 14. The hammer 22 is swing- 25 ably mounted on pivots 24 carried on a pair of spaced mounting plates 25 secured to the tank 14 by suitable means such as screws 26. The hammer is biased to engage the diaphragm 23 by a torsion spring 27.

The hammer is cocked against the action of spring 27 by a manually operable plunger 28 comprising an elong- 30 ated rod carrying, at its lower end, a contact member 29 arranged to selectively abut a corresponding contact portion 30 of the hammer 22. The plunger rod 28 is longitudinally movably carried on a pair of supports 31 projecting from tank 14 and is biased upwardly by a 35 coil spring 32 acting between the lower support 31 and a pin 33 carried by the rod. At its upper end, the rod 28 may be provided with a button 34 for manual engagement by the user.

An electromagnet 35 is carried on the mounting plates 30 25 subjacent the hammer 22. The electromagnet 35 in- 35 cludes a coil 36 and pole pieces 37. The hammer 22 carries on its underside an armature 38 which may be dis- posed in bridging relationship to the pole pieces 37, as shown in FIGURE 2.

65 In operation, the user places in the tank 14 a suitable quantity of the liquid to be dispensed, such as wetting agent liquid L. The liquid may be introduced into the tank through the opening 17. The liquid L flows through the orifice 16 into the pumping chamber 15 and upwardly 70 into the conduit 20. A suitable control, such as control 39, may be provided in the apparatus 10 for effecting an automatic cycle of operation thereof, and including the

provision of an electrical signal at preselected times such as at the time of the final rinse operation of the dishwashing cycle. Herein, the signal may comprise a discontinuation of the energization of the coil 36 of the electromagnet 35. As the user of the dishwasher apparatus 10 may desire the addition of wetting agent only periodically and not with each dishwashing operation, the control 39 is arranged to permit the selective dispensing of the liquid L under the manual control of the user through the use of the plunger 28. More specifically, where no wetting agent liquid L is desired during a dishwashing cycle, nothing need be done by the user. The hammer 22 will be disposed in the upper position of FIGURE 4 under the biasing action of the spring 27, and any signal delivered to the electromagnet 35 will have no effect thereon. However, where the user wishes to dispense a quantity of wetting agent liquid upon provision of the signal to the electromagnet 35, he merely depresses the operator button 34 to urge the contact member 29 downwardly against the hammer portion 30, as shown in FIGURE 4, to swing the hammer downwardly to the position of FIGURE 2 wherein the armature 38 is magnetically latched to the pole pieces 37 as long as magnetizing current is flowing in the coil 36. When the signal interrupting the current flow to the coil 36 is provided, the hammer is released from the electromagnet 35 whereby the force developed by spring 27 quickly swings the hammer upwardly in a counterclockwise direction, as seen in FIGURE 2, to strike the diaphragm 23 and cause displacement of liquid from the pumping chamber upwardly through the conduit 20 and outwardly through the discharge outlet 21. At the same time, a small quantity of liquid in the pumping chamber is caused to flow reversely outwardly through the orifice 16 thereby providing a self-cleaning of the orifice.

The retraction of the hammer 22 to the position of FIGURE 2 permits replacement liquid L to flow through the orifice 16 into the pump chamber for dispensing during subsequent dispensing operations.

Thus, apparatus 10 provides means for dispensing liquids such as a wetting agent during a preselected portion of the cycle of operation of the apparatus, but only when the user potentiates the hammer to effect the desired dispensing. Thus, while the timing of the dispensing is automatically controlled by the apparatus, the determination of whether a dispensing is to be effected or not during a given complete cycle of operation of the apparatus is under the selected control of the user through the medium of the manually operable hammer potentiating plunger 28. As shown in FIGURE 1, the plunger button 34 may be disposed at the rear of the cabinet 10 for facilitated operation of the potentiating member 28 when desired.

Thus, the dispenser 13 is extremely simple and economical of construction, while yet provides an improved selective control utilizing an automatic timing signal of the apparatus with which it is associated. The self-cleaning of the small orifice 16 effectively minimizes maintenance thereof, permitting the orifice to be relatively small to effect a checking action on the reverse flow of the liquid from the pumping chamber back to the tank 14 while yet maintaining the orifice open at all times for normal

flow of the liquid from the tank into the pumping chamber. In the illustrated embodiment, an electromagnetic means is utilized for holding the pumping means comprising the hammer 22 so as to permit the spring 27 to effect the pump stroke. As will be obvious to those skilled in the art, other latching mechanisms such as those utilizing a current pulse to effect a release of the potentiated hammer may be utilized in lieu thereof within the scope of the invention.

While I have shown and described one embodiment of my invention, it is to be understood that it is capable of many modifications. Changes, therefore, in the construction and arrangement may be made without departing from the spirit and scope of the invention as defined in the appended claims.

The embodiment of the invention in which an exclusive property or privilege is claimed is defined as follows:

1. In a liquid dispenser having means defining a pump chamber provided with an outlet, means for discharging a preselected quantity of liquid from said pump chamber through said outlet, comprising:

pumping means disposable in a potentiated arrangement and movable from said potentiated arrangement to provide a pumping stroke forcing a preselected quantity of liquid from said pump chamber through said outlet, said pumping means comprising a flexible diaphragm defining one wall of said pump chamber, a hammer, and spring means for forcibly urging said hammer against said diaphragm; manually operable means for disposing said pumping means in said potentiated arrangement;

means for releasably holding said pumping means in said potentiated arrangement, said holding means comprising an electromagnet and means on said hammer to be held by said electromagnet when magnetizing current is passed therethrough, said manually operable means being arranged to urge said hammer against the spring means to be urged to the potentiated arrangement and held therein by said electromagnet;

means providing a signal at preselected times; and means responsive to said signal for operating said holding means to release the potentiated pumping means whereby said signal means effects a pumping stroke only when said pumping means has been manually potentiated prior to the provision of a signal by said signal means.

2. The liquid dispensing means of claim 1 wherein said signal comprises an interruption in the magnetizing current passed through said magnet.
